UNITED STATES PATENT OFFICE.

EDMUND KUREK, OF CHIPPEWA FALLS, WISCONSIN.

ISOLATION OF GASES.

Application filed August 2, 1924. Serial No. 729,802.

The invention relates to improvements in the isolation of gases.

An object of the invention is to isolate gases from a mixture when their specific 5 weights differ, by subjecting them to the action of centrifugal force to separate them into zones from which they may be removed.

Another object of the invention is to provide means for ozonizing air while it is being subjected to the action of centrifugal force, whereby the ozone may be removed 10 from the zone in which it collects.

The invention further consists in the several features hereinafter set forth and more 15 particularly defined by claims at the conclusion hereof.

In the accompanying drawings: Fig. 1 is 20 a longitudinal sectional view of an apparatus adapted to carry out the invention; and Fig. 2 is a similar view of a modified form of apparatus.

In Fig. 1 of the drawings, 10 indicates a 25 circular vessel which is adapted to be rotated, preferably about a vertical axis, by a shaft 11 journaled in a support 12 and carrying a pulley 13. The upper end of the vessel is provided with a nozzle 14 by which a gas mixture is introduced into the vessel, and gas outlet conduits 15 and 16 extend 30 therethrough into the vessel and have their end portions 17 and 18, respectively, disposed and opening at different radial distances from the axis of the vessel, the end portion 17 being shown adjacent the periphery of the vessel.

When it is desired to produce ozone within the vessel, the upper end 19 of the shaft 11 carries an abrasive wheel 20 rotatable therewith, and a hollow steel tube 21 is disposed co-axially of the vessel through the nozzle 14 to conduct an oxygen bearing gas mixture, such as air. The tube is moved 40 against the abrasive wheel to generate a shower of sparks, which acts on the oxygen 45 of the gas mixture issuing from the end of the tube to form ozone.

In the modified form of the invention shown in Fig. 2, a circular vessel 10' is secured to an upwardly extending shaft 11' 50 by which it is rotated, preferably about a vertical axis, the shaft being journaled in a support 12' and carrying a pulley 13'. The nozzle 14' of the vessel is disposed below for the introduction of a gas mixture, and gas 55 outlet conduits 15' and 16' extend there-

through, the end portion 17' of the conduit 15' extending outwardly and opening near the periphery of the vessel and the end portion 18' of the conduit 16' being disposed at a shorter distance from the axis. 60

For the production of ozone within the vessel, the lower end 19' of the shaft 11' carries an abrasive wheel 20' rotatable therewith, and a steel bar 21 is inserted coaxially into the vessel through the nozzle 14' and 65 is provided with a flared end 22 and a co-axial bore 23 to afford clearance for the end of the shaft projection 19'. An oxygen bearing gas mixture, such as air, is introduced through the nozzle and travels upwardly, 70 adjacent the flared end 22 of the steel bar 21'. The bar is moved against the abrasive wheel to generate a shower of sparks which acts on the oxygen of the adjacent gas mixture to form ozone. 75

In each instance a mixture of gases introduced into the vessel and subjected to the action of centrifugal force by rotating the vessel will separate into its component gases when then differ in specific weight, the heaviest gas seeking the periphery of the vessel. The gases may then be removed while under 80 centrifugal force by conduits opening into the respective zones the gases occupy. If desired the conduits may have their ends 85 opening into the streams of the moving gases to provide a Pitot tube effect.

When air is introduced into the revolving vessel for ozonizing purposes, the steel member is moved against the abrasive wheel to 90 produce a shower of hot iron sparks which converts the oxygen into ozone. The ozone having a greater specific weight than the nitrogen will seek the peripheral portions of the vessel from which it is removed as above 95 set forth, while the nitrogen occupies the inner portion. In the construction of Fig. 2, the nozzle of the container is at the bottom so that there is no tendency for the escape of the lighter gases, such as nitrogen. 100

The invention may also be used for the separation of carbon dioxide from atmospheric mixtures and is of general application in the isolation of gases from a mixture where the specific weights of the component 105 gases differ.

What I claim as new and desire to secure by Letters Patent is:

1. Apparatus for isolating ozone from air comprising a revoluble vessel for sub- 110

jecting air to centrifugal force, metal-grinding abrasive means within the vessel for ozonizing the air and means for conducting the ozone from the vessel.

5. 2. The apparatus for isolating ozone from air comprising a revoluble vessel for subjecting air to centrifugal force, a grinder within the vessel rotating therewith, a metal member bearing on the grinder for producing sparks to ozonize the air and means for conducting the ozone from the revoluble vessel.

15. 3. The method of isolation of ozone from air consisting of centrifugalizing air in a restricted space, simultaneously ozonizing the air by sparks produced by a grinding operation, and removing the ozone from the zone into which it is centrifugalized.

20. 4. Apparatus for isolating ozone from air comprising means for centrifugalizing air including an air-receiving vessel, a metal member disposed within the vessel, an abrasive member disposed within said vessel and relatively rotatable with respect to said metal member and receiving said metal member in engagement therewith for producing sparks to ozonize the centrifugally-influenced air, and means for removing the ozone from the

zone in which it collects when centrifugalized.

30. 5. Apparatus for isolating ozone from air comprising means for centrifugalizing air including an air-receiving vessel, an abrasive member rotatable within the vessel, and an annular steel member surrounding the axis of said abrasive member and bearing on said abrasive member to produce ozonizing sparks, and said annular steel member forming a conduit receiving therethrough air to be ozonized.

35. 6. Apparatus for isolating ozone from air comprising means for centrifugalizing air including an air-receiving vessel, an abrasive member rotatable within the vessel, means for conducting air into said vessel in an axial direction with respect to said abrasive member and into proximity with said abrasive member, metal grinding against said abrasive member about the axis of said member for producing sparks to ozonize the centrifugally-influenced air, and means for removing the ozone from the zone in which it collects when centrifugalized.

40. 45. 50. In testimony whereof, I affix my signature.

EDMUND KUREK.
